COMPACT SHOCKPROOF ELECTRICAL DIS- CHARGE APPARATUS AND MEANS FOR PRODUCING THE SAME

William A. McKay, Essex Fells, N. J., assignor
to Westinghouse Lamp Company, a corporation
of Pennsylvania

Application November 3, 1931, Serial No. 572,785

11 Claims. (Cl. 250—34)

This invention relates to electrical discharge devices and means associated therewith adapted to be employed for a number of different purposes and finds a special application in electrical discharge devices, such as X-ray tubes, rectifying tubes, and the like, and in compact shock proof X-ray apparatus, simple and compact rectifying apparatus and the like.

X-ray apparatus have found extensive use in many different fields and in most of these fields the X-ray tubes employed in said apparatus are operated at voltages ranging from about 40,000 volts upward. These voltages, impressed across the high tension electrode terminals of the tubes, are generally derived from high tension transformers and the like.

Because of the high tension power supplied to the high tension electrode terminals of an X-ray tube, it has been found desirable to design X-ray apparatus so that the tube shall be capable of operating at its working voltage without subjecting the operator or patient to severe electrical shocks or disturbing noises and without any danger of arcing between these terminals.

One of the requirements of such apparatus is that it should be compact so that it may be readily brought into position and especially in the somewhat restricted spaces beneath the common X-ray tables. Moreover, its weight should be as low as possible so that the size of the supporting structure therefor may be a minimum.

Electrical discharge tubes are operated in ambient media having different dielectric strengths or electrical insulating properties. A tube of this character, as for example an X-ray tube, comprises an envelope of glass or the like having a plurality of electrodes hermetically sealed therein, and having the terminals of said electrodes outside of the envelope. At least two of these electrode terminals are connected to a high tension electrical supply in order to impress a relatively high voltage between the electrodes in the tube and are, therefore, called the high tension electrode terminals. An X-ray tube in an ambient medium has its high tension electrode terminals in the ambient medium, with the ambient medium being continuous between these electrodes. The shortest path in this continuous ambient medium between the high tension electrode terminals of an electrical discharge device, such as an X-ray tube, rectifying tube or the like, will hereinafter be referred to as "the ambient medium gap."

It is well known that the ambient medium gap of a tube, or more specifically the shortest path in the continuous ambient medium between the high tension electrode terminals of a tube, must be at least a certain minimum length in order that no external electrical discharge, such as an arc or spark discharge, will take place between these terminals when the tube is operated at its working voltage in that medium, the tube being otherwise designed, as for example, to prevent electrical leakage between the terminals over the exterior surface of the glass envelope. This certain minimum length of the ambient medium gap depends on the particular ambient medium and characteristics thereof, and the working voltage of the tube, and will hereinafter be referred to as the "critical ambient medium gap."

Because oil has a higher dielectric strength than air, an oil immersed tube of a certain working voltage has a critical ambient oil gap which is materially less than the critical ambient gaseous gap of a tube surrounded by a gaseous medium, such as air or the like, and adapted to operate at the same working voltage. Therefore, it has been proposed to employ oil as the ambient medium, so that the distance between the high tension electrode terminals may be materially reduced.

From the time of the advent of the Roentgen tube, however, it has been common practice to operate X-ray tubes in an ambient gaseous medium, such as air. Over this long period of time X-ray tubes operated in an ambient gaseous medium have been of such dimensions that the shortest distance between their high tension electrode terminals measured outside the tube was at least as great as, and generally greater than the necessary critical ambient gaseous gaps between these terminals, consideration also being given to the matter of electrical leakage.

Heretofore it has been proposed to so design X-ray apparatus that they may give some protection from electrical shock and arcing between the terminals of the electrodes upon energization of the X-ray tube. One such means is described in U. S. Patent No. 1,408,989 issued to William D. Coolidge on March 7, 1922. The X-ray apparatus described therein comprises a casing having high tension and filament current supplying transformers therein immersed in oil. Within the casing are provided a plurality of spaced recessed supports mounted on the transformers for carrying an X-ray tube.

The X-ray tube electrodes are electrically connected to the appropriate windings of the trans-

formers and like the transformers are also immersed in the oil. Because the X-ray tube is immersed in oil, which has a higher dielectric strength than air, it is possible for the working voltage of the tube to energize the tube without any arcing outside the tube and between the electrode terminals even when the terminals of the tube are separated by a distance less than the air gap equivalent of the working voltage of the tube.

Because the X-ray tube is immersed in oil, a construction of this character has a number of disadvantages, some of which are as follows: any X-ray tube replacement is an unpleasant and time consuming task because the head of the casing must be removed before the workman may disconnect the electrical tube connections, and the workman must necessarily handle the oil coated tubes and wires; if the X-ray tube should break and the parts of the tube settle on the transformer units it is necessary to drain the oil in order that these parts may be removed; tube replacements generally cannot be made by an ordinary operator but require a skilled operator who comprehends which of the terminals are to be electrically connected to the appropriate leads of the transformer; some of the useful X-rays are absorbed by the oil thus diminishing the effective X-ray output of the apparatus and loss in definition is effected because of the generation of secondary X-rays.

My invention in one of its specific aspects is directed to an X-ray apparatus of the simple, compact and shock proof type which has all of the advantages of the constructions heretofore proposed, without any of the disadvantages heretofore mentioned, and concerns itself not only with X-ray apparatus but with a novel form of X-ray tube as well.

Briefly stated my invention includes a simple and compact X-ray, or other electrical apparatus, of comparatively light weight, which comprises a casing filled with oil and has either one or more transformers contained therein, and a novel compact unit supported by said casing, having its outer surface surrounded by said oil and comprising an X-ray tube, or electrical discharge device, in an ambient medium of air, or the like, and a novel dielectric housing member having means for supporting the tube or device and for cooperating therewith to increase the ambient gap of said tube or device.

The X-ray or electrical discharge tube, also of novel design and contained within said housing member, is supported thereby and has one of its high tension electrode terminals electrically connected to the socket connected to one side of a high tension power source, and its other high tension electrode terminal connected to the other side of the high tension power source by any suitable means. These terminals are spaced from each other a distance measured outside the tube which is materially less than the critical ambient medium gap of the tube, 65 consideration also being given to the matter of electrical leakage, as explained heretofore.

As will be hereinafter more fully described the housing member with its baffle means is so associated with this tube that the tube is capable of operating at its working voltage without external arcing between its high tension electrode terminals, because the ambient medium gap of the tube is so lengthened that it is at least as great as, and preferably greater than its critical ambient medium gap.

An object of my invention is to provide an electrical discharge apparatus which is simple, compact and of light weight and affords adequate protection from the risk of electrical shocks, burns, stray X-radiation and electrical arcing between the high tension electrode terminals and permits ready insertion or replacements of the discharge tube by unskilled persons.

A further object of my invention is to provide an X-ray apparatus of the shock-proof type which embodies an X-ray tube of compact form having a relatively long electrical leakage path between its high tension terminals and capable of operating in an ambient gaseous medium without any arcing outside the tube between its high tension electrode terminals, at the operating voltage of the tube, even though the spaced relation of the terminals of the tube is less than that normally required for such a voltage in that medium.

Another object of my invention is to provide an X-ray apparatus, embodying an X-ray tube adapted to operate in an ambient gaseous medium at its working voltage without any danger of arcing outside of the tube and between its high tension electrode terminals, even when the distance between these terminals, measured outside the tube, is materially less than the minimum length of the ambient gaseous gap for such a voltage in the gaseous medium so that no arcing will occur outside the tube and between these terminals.

Another object of my invention is to provide an X-ray apparatus embodying an X-ray tube in an ambient medium and having a spark over gap between its high tension terminals of a length insufficient to prevent spark over therebetween at the maximum working voltage of the tube, and a means cooperating therewith so that the length of the spark over gap is so increased that no spark over will occur between these terminals in that medium at such voltage.

Another object of my invention is to provide a simple, compact and shock-proof X-ray apparatus adapted to permit X-ray tube replacements in a facile and expeditious manner even by an unskilled operator.

Another object of my invention is to provide a means adapted to be combined with my novel X-ray tube to lengthen the ambient medium gap of the tube per se.

A still further object of my invention is to provide a dielectric means adapted to be combined with an X-ray tube so that the tube is capable of operating in an ambient gaseous medium at its working voltage without outside arcing even though the high tension electrode terminals of the tube measured outside the tube are separated a distance less than its critical ambient gaseous gap.

A still further object of my invention is to provide a shock-proof X-ray apparatus in which tube replacements may be made in a simple manner with the assurance of accuracy in the alignment of the target and without the necessity of further adjustment for subsequent exposures to be taken with the apparatus.

These, as well as other objects of my invention, will be readily apparent from the following specification and appended drawings where-in,

Figure 1 represents a cross sectional fragmentary view, with some of the parts shown in

elevation and others diagrammatically, of an X-ray apparatus embodying my invention;

Figure 2 represents a sectional view along line II-II of Figure 1;

5 Figure 3 is a fragmentary cross sectional view with some of the parts in elevation of a modification of a portion of the apparatus shown in Figure 1;

10 Figure 4 is a fragmentary cross sectional view with some of the parts in elevation of another modification of a portion of the apparatus shown in Figure 1; and

15 Figure 5 is a fragmentary cross sectional view with some of the parts in elevation of another modification of a portion of the apparatus shown in Figure 1.

As shown in Figure 1, one embodiment of my invention includes oil immersed transformer units, an X-ray tube in air, and dielectric baffle 20 members associated therewith to provide an efficient, electrical shock proof, simple, compact and light weight X-ray apparatus which may be expeditiously assembled and repaired.

According to my invention, the X-ray tube 25 may comprise a glass envelope 9, having a cylindrical body portion 10, a generally hemispherical upper end 11 and a lower end in the form of a plurality of suitably spaced cylindrical folds, sleeves or plaits 12, 13 and 14 extending longitudinally of and within the body 10 to provide a relatively long electrical leakage path between the high tension electrode terminals hereinafter referred to.

The innermost plait or fold 14 is substantially 30 shorter than the plaits or folds 12 and 13 and is in the form of an open reentrant tube with a free upper end. Sealed to the free end of this reentrant tube is a tubular metallic sleeve member 15 which supports both an anode 16 and an anode stem 17. This anode stem 17, extending 35 outside of the envelope, surrounded by the reentrant tube, being in line with the anode 16, has a threaded free end.

A second reentrant tube 18, also composed of 40 insulating material, such as quartz, silica or pyrex glass is fused to the inner wall of the fold or plait 13 at a position above the anode sleeve supporting member 15. This reentrant tube 18 surrounds a portion of the anode 16 and like the plait or fold 14 extends longitudinally of and within the tube with its free end uppermost. Between the anode 16 and the inner periphery 45 of the reentrant tube 18 is a spring sleeve 19 firmly secured to the anode and adapted to frictionally engage the inner periphery of the reentrant tube 18 to serve as a shock absorbing and distributing means therefor and also to assist in supporting the anode.

The anode 16 which is preferably composed of 50 copper has a free end 20 which is provided with a target of tungsten or the like and which is capable of emitting X-rays when subjected to electronic bombardment by electrons emitted from a suitable cathode, such as a helical filament 21 of tantalum, tungsten, or any other suitable material.

At the upper portion of the envelope 9 there 55 may be provided a chrome-iron or other suitable X-ray screen of appropriate thickness disposed around the upper end of the anode and serving to screen out undesirable X-rays. This X-ray screen is of reduced length and comprises a cylinder 23 with its bottom edge in the approximate plane of the upper end of the anode 60 16, and a cap 24, having a suitable opening 25

therein adapted to allow a beam of useful X-rays to pass therethrough. Secured to said screen is a spring sleeve 26, the outer surface of which is in frictional contact with the inner periphery of the envelope 9 to hold the screen in position.

Within the screen and near one end thereof is mounted a thin cylindrical open ended focusing member 27 in axial alignment with the longitudinal axis of the anode 16 and the opening 25. The cathode 21, so designed as to have an opening 29 for permitting X-rays produced by electronic bombardment of the target to emerge from the tube by way of the open ended cylinder 27 and the openings 29, 25 and the hemispherical end 11 of the envelope is mounted within the focusing member 27. Lead-in wires 30 are electrically connected to the cathode and have their outer portions hermetically sealed to the envelope and electrically connected to diametrically opposed electrode caps 31 located on the outer periphery of the envelope and in close proximity to the hemispherical portion 11. One of the lead-in wires 30 is electrically insulated from the screen by means of an insulating bead 32 secured to the cap 24.

Each of the terminals 31 is spaced from the anode extension 17 a distance measured outside the tube which is less than the critical ambient medium gap of the tube.

In accordance with my invention I provide dielectric means in combination with the X-ray tube hereinbefore described in order to increase the length of the ambient medium gap. In this construction, hereinafter more particularly described as an illustrative embodiment of my invention, the ambient medium gap of the tube may be so lengthened that the tube may be safely operated at its working voltages in a gaseous medium, such as air or the like, without any danger of arcing between its high tension electrode terminals, even when the distance between these terminals measured outside the tube is materially less than its critical ambient gaseous gap.

That is to say, the tube may be operated at its working voltages without any spark over between its high tension electrode terminals even when the length of the spark-over gap of the tube per se is less than that normally required for these voltages. This result is possible by virtue of means cooperating with the tube to lengthen the path over which the spark would have to travel at these voltages so that the length of the increased spark-over gap is of such a magnitude that no spark-over will occur between these terminals at these voltages.

For this purpose, one of the novel specific dielectric means which I may employ in combination with the X-ray tube hereinbefore described is a substantially cup-shaped member 33 composed of a suitable dielectric material, such as glass, ebonite, hard rubber, porcelain, a phenolic condensation product or the like, and preferably phenolic condensation product because the latter may be readily molded.

The cup shaped member may comprise a single homogeneous phenolic condensation product or glass structure having embedded in its base an electrical conducting socket 34. The cup shaped structure 33 may be further characterized in that it has a cylindrical or a conical wall 35 having a flange 36 extending outwardly therefrom at the upper end thereof, a base 37 and one or more spaced concentric cylindrical baffle 75

members 38 and 39 extending upwardly from the base 37, with the center point of the base being in approximate coincidence with the center line of the respective baffles.

5 The length of the baffles 38 and 39 may be less than the length of the envelope plaits or folds 14 and 13 respectively, and the spacing of these baffles may be such that they readily fit and extend upwardly between the anode extension 17 10 and the plait or fold 14 and between the plaits 12 and 13 respectively upon assemblage of my novel X-ray tube and the dielectric housing 33.

The cup-shaped member 33 may be readily shaped by moulding phenolic condensation product or glass, and the socket 34 may be readily united therewith during the moulding operation to form a fluid tight seal therebetween although any other means of forming a fluid tight seal between the socket 34 and the dielectric cup 20 shaped member 33 may be employed. The socket 34 which is dependably secured to the base of the cup has its upper end free of the dielectric and has a threaded recess inwardly along the axis thereof.

25 That portion of the socket 34 which is outside of and depends from the base 37 has thereon a radiator comprised of a plurality of heat conducting fins 40. This socket 34 has two important and useful purposes, namely, that of an electrical connecting means for the threaded end of the anode stem 17, and that of a heat conducting means which aids in conveying the heat energy from the anode 16. Furthermore it assures accurate positioning of the X-ray tube so 30 that the target is in proper alignment for the taking of X-ray pictures.

The X-ray tube is assembled with the cup-shaped dielectric member by merely screwing the threaded end of the anode extension 17 into the threaded socket 34, to provide a structure as shown in Figure 1 with the cylindrical baffle means 38 and 39 extending upwardly from the dielectric cup 33 and spaced respectively between the anode stem 17 and the plait or fold 45 14 and between the plaits or folds 12 and 13.

The distance between the anode extension 17 and the plait or fold 14, between the plaits or folds 12 and 13, and the distance of the respective cylindrical dielectric baffle members 38 and 39 50 from the center of the base plate 37 are preferably such that when the X-ray tube is screwed into the socket of the electrical conductor 34, the walls of the dielectric baffles 38 and 39 will be free from any hard contact with the folds or 55 plaits of the envelope or the anode extension.

In practicing my invention there may be provided a novel relatively short X-ray tube in an ambient gaseous medium, such as air, and having its high tension electrode terminals 17 and 60 31 spaced from each other, measured outside the tube, a distance indicated by the dot-dash line and being materially less than its critical ambient gaseous gap, and having an envelope characterized by a plurality of spaced plaits or folds 65 12, 13 and 14 at its lower end.

In further accordance with my invention there may be provided a novel, simple, compact shock proof unit of light weight comprising this X-ray tube in an ambient gaseous medium of air or 70 the like together with a dielectric cup 33 surrounding the sides and bottom of the tube envelope and with dielectric baffles 38 and 39 extending upwardly from the bottom of the cup 33 and respectively into the spaces between the 75 folds or plaits 12 and 13 and the anode exten-

sion 17 and the plait or fold 14 to lengthen the ambient medium gap of the tube so that it is at least as great as and preferably greater than its critical ambient medium gap. This X-ray tube embodied in a unit of this construction may be operated at its working voltage without any danger of arcing outside the tube and between its high tension electrode terminals because the length of the shortest path in the continuous ambient gaseous medium between these terminals or the length of what I term "the ambient gaseous gap," indicated by the dotted line, is at least as great as, and preferably greater than, the necessary minimum length of the ambient gaseous gap so that no arcing will take place upon operating the tube in a gaseous medium at its working voltage. This minimum length, as heretofore explained, I term "the critical ambient gaseous gap."

Consequently it is apparent that by employing a unit of this or any generally similar construction the length of the ambient gaseous gap between the high tension electrode terminals of an X-ray tube may be materially greater than the critical ambient gaseous gap even where the 25 distance between these terminals measured outside of the tube envelope is materially less than its critical ambient gaseous gap. By virtue of a construction of this character the length of X-ray tube envelope and anode may be materially reduced to decrease the length of the heat conducting path, minimize the danger of breakage and reduce manufacturing costs, and to provide a compact relatively short tube, having a relatively long electrical leakage path, and 30 adapted to operate without any danger of arcing outside of the envelope between the high tension terminals.

The dimensions of the bottom, sides and baffles of the dielectric cup is a mere matter of 40 economical, mechanical and electrical design depending on the nature of the dielectric, the length of the X-ray tube, the length of the plaits or folds of the envelope, the distance between the high tension terminals, the nature of the 45 ambient medium, and upon the magnitude of the voltage to be impressed between the high tension electrode terminals of the tube.

The unit, comprising the dielectric cup 33 and the X-ray tube associated therewith by 50 means of the anode extension 17 secured to the socket 34, may be connected to any appropriate electrical supply, and may be supported by any suitable means.

It may be preferably combined with an oil 55 filled transformer casing 41 in order to provide a compact means adapted to be readily mounted on a supporting structure and so that the oil in the casing may exert a cooling action on the anode by virtue of the fins 40 and a portion of the socket 34 being immersed therein.

The transformer casing 41 is of any appropriate size and has a top 42 with a circular opening of suitable diameter which permits the insertion therein of the tube housing dielectric cup 33. The flange 36 of the cup rests on the top plate 42 of the casing and is firmly secured thereto to form an oil tight seal therewith to prevent any leaking therethrough of the oil which surrounds the outer surface of the cup 70 and a plurality of transformers 43 and 44 totally immersed therein.

The transformers 43 and 44 are respectively high tension and low tension transformers, with primary windings 45 and 46, each connected 75

across a suitable power supply 47, and having secondary windings 48 and 49 respectively. One terminal of the secondary winding 48 of the high tension transformer is connected to the 5 free end of the socket 34 by means of a connecting wire 50 and the other end of this secondary winding 48 is connected to one of the cathode terminals 31 by means of a wire 51 and a spring clip connector (not shown).

10 The cathode filament 21 is heated by means of current from the low voltage transformer 44 having one terminal of its secondary winding 49 electrically connected to the cathode terminal 31 by means of a wire 52 and a spring clip (not shown) and the other terminal of this winding 49 is connected to the first mentioned cathode terminal 31 by means of a wire 53 connected thereto and to the high tension wire 51.

15 To provide additional safeguards against any 20 danger of electrical shocks, I preferably electrically connect by means of a wire 54 the casing with one of the terminals of the secondary winding 48 of the high tension transformer, and ground the casing in any suitable manner by 25 means of the ground connection 55.

20 In order that the X-ray bulb may be completely surrounded with a protective medium, I provide a cap 56 of bakelite or any other suitable material over the hemispherical portion 11 30 of the envelope of the X-ray tube and secured to the top of the transformer casing in any suitable manner.

25 Although the screen, oil and transformer casing absorb substantially all of the undesirable X-radiation, a lead band 57, preferably but not necessarily secured to the inner side of the bakelite structure 35, may be provided to overlie the juncture between the cap 56 and the cup 33 and may be of such a width as to extend upwardly an appreciable distance along the inner surface of the cap and downwardly an appreciable distance along the wall of the bakelite cup 33 to absorb any undesirable stray X-radiation which might not be absorbed by 40 the screen, oil or transformer casing. This band may be electrically connected to the cathode terminal by any suitable means.

45 The cost of manufacturing X-ray apparatus, and particularly the X-ray tube per se, may be 50 materially reduced by employing a transformer casing and a dielectric cup of sufficient depth so that the upper level of the oil within the casing is in close proximity to and preferably materially above the upper limit of the envelope of 55 the tube. In a construction of this character, the cylindrical portion 23 of the metallic screen may be completely eliminated because the oil and the transformer casing will absorb any undesirable X-radiations. Therefore, in place of 60 the screen heretofore described I may employ a screen consisting of a circular plate, similar to plate 24 of appropriate thickness and having an opening therein and a spring sleeve, similar to sleeve 26, secured to the outer periphery of the 65 plate by means of suitable pins.

65 It is also within the scope of my invention to have the unit embodying X-ray tube and the dielectric cup mounted on any suitable supporting means other than and remote from the 70 transformer casing.

75 Although I have described one embodiment of my invention with particularity, I am not limited to this embodiment because the invention is susceptible to a number of modifications. It is within the purview of this invention to include

an X-ray apparatus, as shown in Figure 5, similar in all respects to the construction shown in Figure 1, except that the X-ray tube may have but one reentrant fold or plait of convenient length suitably spaced from the anode extension, and the bottom of the dielectric housing may have but one dielectric cylindrical baffle of appropriate dimensions extending upwardly and into the space between the anode extension and the reentrant fold or tube.

10 Another modification of my invention is shown in Figure 3 and is similar in all respects to the construction shown in Figure 1 except that the bottom of the dielectric cup has but one cylinder baffle 39 which baffle is located between the folds 15 12 and 13 of the X-ray tube.

15 A further modification of my invention comprises a structure similar in all respects to the structure shown in Figure 1 except for certain modifications illustrated in Figure 4 and hereinafter described.

20 In the construction shown in Figure 1, the dielectric baffle means 38, located between the anode stem 17 and the plait or fold 14, is integral with the bottom of the dielectric housing 25 member 33. Instead of having the baffle means located between the anode stem and its adjacent plait or fold, integral with the bottom of the dielectric housing member, I may provide a cylindrical baffle means 60, with its inner wall spaced 30 from the anode stem and rigidly secured thereto by an inwardly extending flange 61 at the upper end of the cylindrical baffle means 60 and an integral part thereof.

25 The lower or free end of the baffle means 60 is appropriately threaded, and the bottom of the dielectric cup or housing member has an appropriately threaded recess 62 adapted to form 35 a tight joint with the threaded end of the baffle means. In a construction of this character there 40 is provided an X-ray tube similar to the one heretofore described and differing therefrom in having a dielectric baffle member rigidly secured to its anode stem.

35 This X-ray tube may readily be secured to the modified dielectric housing by simultaneously 45 screwing the threaded free end of both the baffle member and the anode extension into the threaded recess of the dielectric housing member and the electric socket respectively.

45 By the term "working voltages" of the tube as hereinbefore referred to and as employed in the appended claims, I mean the normal operating voltages of the tube and also the surge voltages caused by the energization and deenergization of the tube on the "make" and "break" 50 of its circuit, the latter of which are considerably greater than the former.

55 Although I have described the invention with specific reference to X-ray tubes it is obvious to 60 those skilled in the art it may be applied to other electrical discharge devices, such as rectifier apparatus and tubes and the like.

65 What is claimed is:

1. An X-ray tube housing comprising a chamber composed of dielectric material, a socket secured to said chamber, said socket being adapted to receive the anode terminal of an X-ray tube, a radiator secured to said socket and extending outwardly from said chamber, a plurality of dielectric walls united to a wall of said chamber in the proximity of said socket and extending from said wall said dielectric walls being located within said chamber.

70 2. An X-ray tube housing comprising a dielec-

tric chamber having a base and a side wall, a socket secured to said base and forming an oil tight seal with said base, a radiator secured to said socket and extending outwardly from said base, a plurality of dielectric walls secured to said base, each dielectric wall forming an annulus with the side wall of said chamber.

3. An X-ray apparatus including a dielectric chamber, an electric conductor in one wall thereof, dielectric baffle means in said chamber and extending from an inner wall surface thereof, and an X-ray tube having an envelope and a plurality of high tension electrode terminals, one of said terminals being electrically connected to said conductors, the distance between said terminals measured outside of the tube when not mounted being less than the critical ambient gap of the tube, said tube being mounted in said chamber, said baffle means being adjacent a wall of said envelope and spaced therefrom, the length of the ambient gap of the tube mounted being as great as said critical gap.

4. An X-ray apparatus including an X-ray tube in air and having high tension electrode terminals and an envelope, the shortest distance between said terminals measured outside of said tube when not mounted being less than the critical ambient air gap of said tube, and a dielectric chamber having an electric socket in one of its walls, and dielectric baffle means in said chamber, said X-ray tube being mounted in said chamber and having one terminal thereof in said socket, said baffle means being adjacent a wall of said envelope, the length of the ambient air gap of the so mounted tube being as great as the critical air gap of said tube.

5. An X-ray apparatus including an X-ray tube in air, said tube having an envelope, a cathode terminal and an anode terminal, the shortest distance between said terminals measured externally of said tube when not mounted being less than the critical ambient air gap of the tube, a dielectric chamber having an electrical socket in one of the walls thereof, dielectric baffle means in said chamber and extending from one of the walls thereof, said envelope having a body portion and dielectric means integral therewith, said dielectric means having a portion thereof spaced from said body portion, said X-ray tube being mounted in said chamber with the anode terminal being located in said socket, said dielectric baffle means being located in the space between said dielectric means and said body portion of said X-ray tube, the length of the ambient air gap of the so mounted tube being as great as the critical ambient air gap of the tube.

6. An X-ray apparatus including an X-ray tube having an envelope and spaced high tension electrode terminals, a portion of said envelope being in the form of a plurality of sleeves, one of said sleeves being integrally united with and having a portion thereof spaced from another sleeve, a dielectric chamber having an electric socket in one wall thereof, and dielectric baffle means in said chamber and extending from the inner wall surface thereof, said tube being mounted in said chamber with said baffle means located in the space between said sleeves, one of said terminals being electrically connected to said socket.

7. An X-ray apparatus including an X-ray

tube having an envelope and spaced high tension terminals, the envelope having a portion thereof in the form of a plurality of spaced cylinders, and a dielectric chamber, said chamber having an electric socket in one wall thereof, a cylindrical dielectric baffle extending from the inner wall surface of said chamber, said tube being located in said chamber, one of said terminals being electrically connected to said socket, said baffle being located in the space between said cylinders. 10

8. An X-ray apparatus including an X-ray tube having an envelope and spaced high tension electrode terminals a portion of said envelope being in the form of spaced folds, a dielectric chamber, said chamber having a dielectric 15 baffle means secured thereto and extending from the inner wall surface thereof, said tube being located in said chamber, said baffle being located in the space between said folds, said chamber having an electric conductor therein one of 20 said terminals being electrically connected to said conductor.

9. An X-ray apparatus including an X-ray tube having an envelope and spaced high tension electrode terminals, said envelope having a 25 portion thereof in the form of spaced concentric cylinders, a dielectric chamber having a conductor secured thereto, a cylindrical baffle means secured to said chamber and located therein, said tube being located in said chamber, one of 30 said terminals being electrically connected to said conductor, said cylindrical baffle being located in the space between said spaced cylinders.

10. An X-ray apparatus including an X-ray tube in air and having an envelope and high tension electrode terminals, a casing containing oil and a transformer immersed therein and connected to said X-ray tube for energizing the same, a dielectric chamber carried by said casing and being immersed in said oil, an electric conductor secured to one of the walls of said chamber, said X-ray tube being mounted in said chamber, one of said terminals being electrically connected to said conductor, the distance between the electrode terminals of said tube measured outside of said tube and when not mounted being less than the critical ambient air gap of said tube, said dielectric chamber including dielectric baffle means for increasing the ambient 50 air gap of the tube, the ambient air gap of the tube when mounted in said chamber being at least as great as the critical air gap of the tube.

11. An X-ray apparatus including an X-ray 55 tube in air and having an envelope and a plurality of spaced high tension terminals, said envelope having a portion thereof in the form of a plurality of spaced cylinders, a casing, a dielectric liquid in said casing and a transformer 60 immersed in said liquid and connected to said X-ray tube for energizing the same, a dielectric chamber carried by said casing and immersed in said liquid, a dielectric baffle secured to said chamber and extending from the inner wall surface thereof, a socket carried by said chamber, one of said terminals being located in said socket, said tube being located in said chamber, said baffle being located in the space between said spaced cylinders. 65
